[57] CLAIM

The ornamental design for a hand operated crimping tool, as shown and described.

DESCRIPTION

FIG. 1 is a side elevational view of a hand operated crimping tool showing our new design;

FIG. 2 is an elevational view showing the side opposite that shown in FIG. 1;

FIG. 3 is a front elevational view; and

FIG. 4 is a top plan view thereof.

The undisclosed rear surfaces of the crimping tool are conventionally flat and unadorned.

FIG.1

FIG.2
